UNITED STATES PATENT OFFICE.

DOMINIC FRIZ, OF RAMSAY, MICHIGAN.

DESIGN FOR A BIRD-CAGE.

52,474.

Specification for Design. Patented Sept. 24, 1918.

Application filed July 15, 1918. Serial No. 245,120. Term of patent 14 years.

To all whom it may concern:

Be it known that I, DOMINIC FRIZ, a citizen of the United States, residing at Ramsay, in the county of Gogebic and State of Michigan, have invented a new, original, and ornamental Design for Bird-Cages, of which the following is a specification, reference being had to the accompanying drawings, forming part thereof, in which—

Figure 1 is a side elevation of a bird cage showing my new design;

Fig. 2 is an end elevation; and,

Fig. 3 is a top plan view.

I claim:

The ornamental design for a bird cage as shown.

DOMINIC FRIZ.
